FIRE FIGHTING APPARATUS

Otto B. Hisaw, Susanville, Calif.

Application January 13, 1939, Serial No. 250,823

1 Claim. (Cl. 169—24)

My invention relates generally to fire fighting apparatus for operation without a pressure water supply, and particularly to ambulatory apparatus of this character which will take water from any available water supply into a reservoir tank included therein, and discharge the water with sufficient force for fire extinguishing purposes, and an important object of my invention is to provide a simple, efficient, and relatively inexpensive fire fighting apparatus of the character indicated which is especially adapted for use and operation in extinguishing grass, brush, and forest fires and fires occurring in communities lacking pressure water supply.

Other important objects and advantages of my invention will be apparent from a reading of the following description taken in connection with the drawings, wherein for purposes of illustration I have set forth a preferred embodiment of my invention.

In the drawings—

Figure 1 is a general side elevational view of the embodiment.

Figure 2 is a top plan view of Figure 1.

Figure 3 is a rear end elevational view thereof.

Figure 4 is a fragmentary and enlarged top plan view of the vehicle transmission power take-off partly in section.

Figure 5 is a fragmentary isometric schematic view showing the components of the embodiment in operative relation.

Referring in detail to the drawings, the numeral 5 generally designates the fire fighting apparatus of the present invention as a whole and this is made up of a suitable automobile truck involving a platform 6 mounted on the wheeled chassis 7 to the rear of the cab 8, on which platform is mounted an elongated water tank 9 which is provided at longitudinal intervals with interior baffles 10 preventing surging of the water while the truck is in motion. The truck has a conventional transmission 11 conventionally located, but having mounted on one side the power take-off 12, as shown in Figure 4 which involves a gear box 13 having a gear 14 adapted to be moved by the control lever 14' into mesh with one of the gears of the transmission, the last-mentioned gear not being shown. The gear 14 is mounted on a jack shaft which includes the belt pulley 15 over which the belt 16 is trained. This belt 16 is also trained over the pulley 17 on a rotary force pump 18 which is mounted on the forward end of the platform 6 at one side of the tank 9.

To the intake side of the force pump 18 is connected a pipe 19 to which is connected a flex-

ible hose 20 which is adapted to be placed in a suitable water supply such as a stream, lake, water barrel or the like source of water which may be available. The pipe 19 has therein the shut-off valve 21 and between the valve 21 and the pump is the branch 22 which is equipped with a shut-off valve 23, the pipe 22 being in communication with the lower part of one side of the tank 9.

10 The discharge side of the force pump 18 has connected thereto a pipe 24 which has on its upper end an L-shaped swivel joint 25 to which is connected the flexible fire-fighting hose 26 which includes the stream controlling nozzle 27. 15 The joint 25 has the shut-off valve 25'. A branch pipe 28 is connected to the pipe 24 between the discharge side of the pump and the swivel 25, and this pipe 28 leads into the top of the tank 9, the pipe 28 having a shut-off valve 29 located between the pipe 24 and the tank 9.

20 By reason of the arrangements described the tank 9 may be filled with water coming through the flexible pipe 20 by opening the valve 21, shutting the valve 23 and opening the valve 29 with the force pump 18 operating, whereby the water drawn through the flexible pipe 20 will pass through the pipe 19 up through the pipe 24, over through the pipe 28 and into the top of the tank 9. If desired the valves 23 and 29 may be closed, 25 with the valve 21 open, and with the pump 18 operating, the water drawn into the flexible pipe 20 may be forced directly through the fire-fighting hose 26 for discharge upon the fire. In the event that the water in the tank 9 is the sole supply of water, the valves 21 and 29 are to be closed, with the valve 23 open, so that the pump 18 30 will suck the water through the pipe 22 from the tank 9 and through the pipe 19, and force the water through the pipe 24 through the valve 25' to the hose 26.

35 Along the left hand side of the platform 6 and mounted in suitable journals 30 thereon is the rotary valve operating rod 31 which has a handle 32 within reach of the operator of the truck in the cab 8, and the rear end of this shaft 31 has thereon a beveled pinion 33 which is in mesh with another beveled pinion 34 on a rotary valve operating shaft 35 which operates the shut-off valve 36 in a pipe 37 leading out from the lower part of the back of the tank 9. The pipe 37 40 has a downward bend 38 which terminates in communication with and in supporting relation to a transverse horizontal spray pipe 39 which is formed in its bottom with perforations to emit streams of water for the purpose of putting out

grass fires and the like, the same being under constant control by the operator of the truck by means of the handle 32.

Alongside of the pipe 35 and on the back of the platform 6 is a manual force pump 40 which includes the operating lever 41, and the discharge side of this manual pump includes an intake pipe 42 which may be connected with a flexible intake pipe such as the pipe 20 leading from a suitable supply of water. The discharge side of this pump includes a gooseneck 43 which is adapted for connection to a suitable fire-fighting hose such as the hose 26. The manual pump is to be utilized in the event of failure of the force pump mechanism or in the case of an absence of water in the tank 9, and to prime the force pump when necessary.

Although I have shown and described herein a preferred embodiment of my invention, it is to be understood that I do not limit the application of my invention thereto, and any change or changes may be made in the structure arrangement of the parts within the spirit of the invention and the scope of the subjoined claim.

Having described the invention, what is claimed as new is:

Means for delivering liquid to or from a tank of a motor vehicle comprising a pump driven from the power plant of the vehicle and located on the vehicle at one side of the tank, a pipe line connected with the inlet of the pump, a branch pipe connecting an intermediate part of the pipe line with a lower part of the tank, a valve in said branch line, a valve in the pipe line between the junction therewith of the branch line and that end of the line which is opposite the end connected with the pipe, means for connecting a hose to the valve carrying end of the pipe line, 10 a vertically arranged pipe connected with the outlet of the pump, a second branch line connecting said vertical pipe adjacent its upper end to the top of the tank for leading water from the pump into the tank, a valve in said second branch line, an L-shaped pipe swivelled to the upper end of the vertical pipe and adapted to have a hose connected therewith and a valve in the L-shaped pipe.

OTTO B. HISAW.
